RAILWAY DRAFT GEAR

Donald S. Barrows, Rochester, N. Y., assignor to
The Gould Coupler Company, New York, N. Y.,
a corporation of Maryland

Application October 12, 1929. Serial No. 399,270

2 Claims. (Cl. 213—30)

The invention relates to draft gears for railway cars, and aims to provide a short, compact gear which is adapted for application to cars having a relatively short overhang, such as ore cars, and which, though of comparatively short travel, secures a high degree of cushioning effect.

In addition to the general object just stated, the invention has for further objects such other improvements and advantages in construction and operation as may be attained by the structures and devices hereinafter described or claimed.

In the drawing which illustrates embodiments of the invention:

15. Figure 1 is a plan view of one form of the improved draft gear assembled with a yoke and a draw bar.

Figure 2 is a view, partly in side elevation and partly in vertical section, of the gear shown in 20 Figure 1.

25. Figure 3 is a fragmentary vertical section of another form of draft gear.

The draft rigging illustrated in the drawing and provided with an embodiment of draft gear according to the invention, is a type especially suitable for railway cars, such as ore cars, which have a relatively short overhang. The rigging includes the draw bar 11 of a coupler and a horizontal yoke 12 shortened consistently with the 30 compact draft gear positioned within the gear pocket provided by the yoke.

The illustrative draft gear includes outer friction elements or housing members 13 and 14, relatively movable longitudinally, and twin cushioning devices, between the housing members which operate transversely and function yieldingly to oppose relative approach of the housing members in both buff and draft. In buff, the rear housing member 14 is held by the usual backstop engaging the rear end of the yoke 12 which embraces the rear surface of the housing member, and the front housing member 13 is moved rearwardly by the butt end of the draw bar 11 toward the rear housing member 14, which movement effects compression of and frictional resistance by the twin cushioning devices. During the buffing movement, the front housing member carries with it the key 15 which slides in elongated key slots 16 in the yoke arms and in elongated slots provided in the usual cheek plates and/or draft sills (not shown). In draft, the front housing member 13 is held by the engagement of the key 15 with the front end of the slot in the cheek plate and the rear housing member 14 is moved forwardly by the pull applied

from the rear end of the yoke 12, to operate the cushioning devices.

According to ordinary manufacturing practice, the housing members 13 and 14 may be metal castings. The front housing member 13 is preferably in the form of a box-like structure having an open rear end 17, and comprising a flat vertical front wall 19, reduced in area as compared with the rear end 17, parallel side walls 9 connecting the front and rear ends, and rearwardly diverging top and bottom webs 21 and 22 respectively sloping upwardly and downwardly from front to rear of the front housing member. If desired, the top and bottom webs 21 and 22 may be provided each with a pair of longitudinal reinforcing flanges 25 which augment the resistance of the webs 21 and 22 to shocks. The rear housing member 14 consists of a somewhat similar box-like structure, having an open end 18 facing the rear open end 17 of the front housing member, a vertical rear wall 20 reduced in area as compared with the front end 18, parallel side walls 10 connecting the rear and front ends, and forwardly diverging top and bottom webs 23 and 24 respectively sloping upwardly and 65 downwardly from rear to front of the rear housing member.

The interior of the front housing member 13 is divided by a transverse partition 47 centrally positioned vertically to provide recesses 26 which extend forwardly from the rear end 17 within the housing member. These recesses 26 are arranged transversely, and preferably vertically, in respect of the line of movement of the front housing member. Similarly arranged recesses 27, 90 companion to the recesses 26, are provided by the vertically centrally positioned partition 48 in the rear housing member 14. The recesses 27 extend from the front open end 18 of the rear housing member and rearwardly within the 95 housing member. Each recess 26 and 27 has top and bottom friction faces 28 and 29 sloping respectively downwardly and upwardly from the open end of the recess to the inside terminal wall 30 thereof. The outer portions 31 and 32 of the friction faces 28 and 29 are offset respectively below and above the main planes of the faces, and the shoulders 33 connecting said offset portions 31 and 32 with the main body portions of the friction faces function as limiting 100 stops for the friction wedges connecting the two housing members of the gear. As above described, the twin recesses 26 and 27 conjointly provide twin pockets arranged transversely of the line of movement of the housing members, 110

for receiving concurrently operable twin cushioning devices which yieldingly oppose relative approach of the housing members, in both buff and draft.

5 The twin cushioning devices comprise the top and bottom wedge and spring assemblies 34 and 35, respectively seated in the pockets provided by the housing members. Each assembly consists of a pair of intermediate friction elements 10 or wedges 36 and spring elements, such as the two sets of oppositely curved leaf springs 37 interposed between the wedges of the pair and operating vertically on said wedges to move them apart and respectively into frictional engagement 15 with the inclined top and bottom friction faces 28 and 29 of the pockets in the housing members. The outer faces at the top and bottom respectively of the wedges 36 of each pair are formed with downwardly and upwardly sloping friction surfaces 38 and 39 complementary to the friction surfaces 28 and 29 of the recesses 26 and 27. These friction faces of the wedges are provided with upwardly and downwardly offset portions 40 and 41 and shoulders 42 engaging 20 the shoulders 33 to limit relative recessional movement of the housing members and to hold the parts of the gear in assembled relation.

The sets of springs 37 seat within pockets 43 provided in the wedges 36 by surrounding vertical flanges 44. The curved surfaces of the sets of leaf springs 37 are in mutual engagement and the springs press the wedges 36 outwardly so that the wedges are interlocked normally within the pockets of the housing members. The gear 35 may be assembled by pressing the housing members 13 and 14 over the ends of the assembled wedges 36 and springs 37 until the companion shoulders 33 and 42 interlock, and may be taken apart by forcing the wedges together to disengage 40 the interlocking shoulders.

The front housing member 13 may be constructed to function as a combined follower block and housing member, thereby dispensing with an ordinary front follower block. For this purpose, the front housing member is provided with a horizontally elongated key slot 45 for the key 15. The key slot is centrally positioned vertically in the housing member and extends rearwardly between the top and bottom recesses 26 and in 45 a lapping relationship with said recesses. The recesses respectively extend forwardly from the rear open end 17 of the member and terminate forwardly of the rear end of the key slot 45.

As shown in Figure 2, the rear housing member 14 is rounded off at the corners 49 connecting the side walls 10 with the rear wall 20. These corner portions 49 are rounded to fit the inside radii of the yoke 12 at the corners connecting the side arms with the rear end thereof and extend below the corner shoulders 50 of the rear housing member. In the assembly of the parts, the shoulders 50 overlie the yoke corners and assist in positioning the rear housing in the yoke.

In the form shown in Figure 3, the gear is 65 constructed to permit the use of a rear follower 46 between the rear wall 20 of the rear housing member 14 and the rear end of the yoke 12. In this form, the rear follower 46 is provided with a pair comprising upper and lower forwardly projecting bosses 51 which enter corresponding holes 52 in the rear wall 20 of the rear housing members. This construction maintains the housing

member and rear follower in alignment and prevents the housing member from sagging.

Although I have disclosed certain preferred embodiments of my invention, it will be understood that modifications may be made within the spirit and scope of the appended claims. 80

What is claimed is:

1. Cushioning mechanism adapted for use with railway draft rigging comprising a front friction element formed with a rearwardly extending wedge-shaped portion and outer inclined walls providing a pocket on either side thereof, said element being adapted to function as a front follower and provided with a transverse slot to receive a horizontal draft key, said slot extending into the wedge-shaped portion for decreasing the necessary length of the element, a rear friction element formed with a forwardly extending wedge-shaped portion and outer inclined walls providing pockets complementary to the pockets in the front element, both of said wedge-shaped portions and the inclined walls of the elements providing transversely disposed inclined friction surfaces, friction shoes positioned between said front and rear friction elements and formed with 100 correspondingly inclined friction surfaces, one of said shoes engaging the inclined surfaces on one side of the wedge-shaped portions, and another engaging the inclined surfaces on the other side of the wedge-shaped portions, the remaining shoes being disposed outwardly of said first-mentioned shoes and cooperating therewith and with the inclined surfaces on the outer walls of said front and rear friction elements, said friction shoes having pockets opening toward one 110 another, and resilient means positioned in said pockets to urge said friction shoes into engagement with the friction surfaces on the wedge-shaped portions and inclined walls of the elements. 115

2. Cushioning mechanism adapted for use with railway draft rigging comprising a front friction element formed with a rearwardly extending wedge-shaped portion and outer inclined walls providing a pocket on either side thereof, said element being adapted to function as a front follower and provided with a transverse slot to receive a horizontal draft key, a rear friction element formed with a forwardly extending wedge-shaped portion and outer inclined walls providing 120 pockets complementary to the pockets in the front element, both of said wedge-shaped portions and the inclined walls of the elements providing transversely disposed inclined friction surfaces, friction shoes positioned between said front and rear friction elements and formed with correspondingly inclined friction surfaces, one of said shoes engaging the inclined surfaces on one side of the wedge-shaped portions, and another engaging the inclined surfaces on the other side 130 of the wedge-shaped portions, the remaining shoes being disposed outwardly of said first-mentioned shoes and cooperating therewith and with the inclined surfaces on the outer walls of said front and rear friction elements, said friction shoes having pockets opening toward one 135 another, and resilient means positioned in said pockets to urge said friction shoes into engagement with the friction surfaces on the wedge-shaped portions and inclined walls of the elements. 140
